UNITED STATES PATENT OFFICE.

FRANKLIN G. HOBART AND CHARLES B. JAHNKE, OF BELOIT, WISCONSIN, ASSIGNEES
TO FAIRBANKS, MORSE & COMPANY, OF CHICAGO, ILLINOIS, A CORPORATION OF
ILLINOIS.

MOVABLE OIL INJECTOR.

Application filed September 8, 1919. Serial No. 322,592.

To all whom it may concern:

Be it known that we, FRANKLIN G. HOBART and CHARLES B. JAHNKE, citizens of the United States, residing at Beloit, in the 5 county of Rock and State of Wisconsin, have invented a certain new and useful Improvement in Movable Oil Injectors, of which the following is a specification.

This invention relates to oil burning engines, particularly those of the type using 10 heavy oil in which, on starting the cold engine, the spray of oil is directed against a certain part of the combustion chamber, specially heated for ignition purposes, and 15 is thereafter directed to another part for the regular operation of the engine.

The object of the invention is to provide an oil injector for use in mechanism of this 20 class in which the injector itself is movable to so change the direction of the stream of oil.

The invention consists in mechanism capable of carrying out the foregoing objects which can be easily and cheaply made, 25 which is satisfactory in operation, and not readily liable to get out of order. More particularly, the invention consists in features and details of construction hereafter more fully set forth in the specification and 30 claims.

The single figure of the drawing is a section thru mechanism illustrating this invention in its preferred form. It shows conventionally the upper end 2 of an engine 35 cylinder having passage 4 leading to the piston (not shown) covered by cylinder head 6 containing a combustion chamber 8, partially water jacketed as at 10, there being at one side of this chamber 8 the initially specially heated mechanism 12 here 40 shown as an electrical device.

The problem to be solved by this invention is the installation in connection with this chamber 8 of an injector mechanism 45 which may be selectively moved, at the will of the operator, outside the chamber to throw oil against the heater 12 or to some other part of the chamber as, for instance, along the arrow headed line 14 into the passage 4.

The desired result is accomplished by the mechanism shown in the upper portion of the figure which consists of the following mechanism: In an opening made in the top 55 of the combustion chamber 8 at an angle to

the line 14 heretofore referred to, being the central axis of the cylinder and the chamber 8, is inserted an injector case 16 contacting the combustion chamber 8 in a close fit on the surface 18 so the water jacket in space 10 will cool case 16. This case is drawn 60 tight against surface 18 referred to and secured in place by bolts or other means outside the combustion chamber forming no part of this invention and therefore not 65 shown.

Journalized on the central axis of this case 16 is a rotatable injector member 20 large enough at its lower end to take annular bearing at 22 against the lower portion of 70 case 16 and be thus held against upward movement with reference to the case and small enough at its upper end to be enclosed by the sleeve 24 rigidly held in place by a nut 26 bearing on handle member 28, 75 nonrotatably positioned by a key or the like 30. The sleeve 24 is rotatable in the stuffing box packing mechanism 32—34—36, of obvious construction, attached to the end 80 of case 16. The lower end of sleeve 24 terminates in an oil space 36 occupying the central portion of the interior of the case 16 and is engaged by the upper end of a spring 38 whose lower end rests upon a washer 40 supported from below on inclined 85 faces 42 provided for it in the inner wall of the case 16. Spring 38 tends to move the entire injector member upward and thus force its lower large end against inclined faces 22. The chamber 36 is supplied with 90 fuel oil by any suitable pipe connection 44. The washer 40 does not occupy the entire cross-section of the chamber 36, but is constructed to allow oil to pass into the annular space 46 communicating with angular 95 passage 48 leading to the approximate lower center of the injector member 20 where it opens into a large passage 50 inclined sharply away from the central axis of member 20. Passage 50 is entered by the injector nozzle 52 having at its outer end a discharge port nozzle 54 and at its inner end a spring pressed ball valve 56 operating in the usual way to permit under normal conditions, flow of oil from pipe 44 outward 100 thru the injector nozzle port 54 and to prevent the return of such oil with or without 105 gases of combustion when the engine charge is fired.

The angularity of injector case 16 to the 110

center line 14 of the engine and the angularity of passage 50 to the central axis of the movable member 20 of the injector is such that with the parts in position shown in the figure, oil delivered from injector nozzle port 54 will pass directly to the initial firing mechanism 12 and that when handle 28 is given an angular rotation from the position shown the nozzle port 54 will be directed to and deliver oil to a different part of the hot chamber 8. The particular device here illustrated is so designed that when handle 28 is rotated 180 degrees from the position shown nozzle port 54 will direct fuel down passage 4. Obviously by varying the angularity of the injector with reference to combustion chamber 8 and by varying the angularity of discharge passage 50 to the injector itself the device may in initial design be made to shift the direction of the stream of delivered oil between almost any two selected points in the chamber 8.

Having thus described our invention what we claim as new and desire to secure by Letters Patent is:—

1. In mechanism of the class described, a stationary injector case adapted to be positioned to deliver oil to an engine, a rotatable injector member mounted within said case, there being a passage angular to central axis of the injector member thru which oil is discharged leading from a point in the side of and intermediate of the ends of the in-
- jector member to the operating end of the injector member, means supporting the injector member against longitudinal movement with reference to the case, and means for supplying oil from the outside to the interior of the injector case and to said discharge passages, for the purposes set forth.

2. In mechanism of the class described, an injector case, a rotatable member mounted within the case having at one end an enlarged portion taking bearing adjacent to the end of the case to prevent movement of the member to the case, a stuffing box mechanism at the other end of the case preventing leakage of oil at that end of the case, a spring mechanism in a space formed in the interior of the case adapted to move the rotatable member in a direction to hold this enlarged end against the end of the case while permitting rotation of the inner member, means for rotating said member, means supplying fuel material from outside the case to said passage which contains the spring and thence to a discharge passage leading from and thru the enlarged end of the rotatable member and at an angle to the central axis of the injector, for the purposes set forth.

In witness whereof we have hereunto subscribed our names.

FRANKLIN G. HOBART.
CHARLES B. JAHNKE.
